United States Patent Office.

HENRY LOTH, OF PHILADELPHIA, PENNSYLVANIA.

Design No. 4,604, dated January 24, 1871.

DESIGN FOR A SEWING-MACHINE STAND.

The Schedule referred to in these Letters Patent and making part of the same.

I, HENRY LOTH, of Philadelphia, county of Philadelphia, State of Pennsylvania, have invented or produced a Design for a Sewing-machine Stand, of which the following is a specification.

In the accompanying drawing—

Figure 1 represents a sewing-machine stand made in accordance with my design, and

Figure 2, the same, showing a slight modification.

The design consists of a light open sewing-machine stand, of the character shown in the drawing, furnished at one end with a case of drawers, A, which may either be secured to the stand adjacent to one of the end frames or legs, as shown in fig. 1, or be made of sufficient length to support one end of the stand, as seen in fig. 2.

Irrespective of the arrangement of the mechanism upon the stand, or of the ornamentation of the latter, I claim—

The design for a sewing-machine stand, substantially as described, and as represented in and by the accompanying drawing.

In testimony whereof I have signed my name to this specification in the presence of two subscribing witnesses.

HENRY LOTH.

Witnesses:

WM. A. STEEL,
FRANKLIN B. RICHARDS.
